UNITED STATES PATENT OFFICE.

GUY W. SMITH, OF SAN JOSE, CALIFORNIA.

OIL-BURNER.

SPECIFICATION forming part of Letters Patent No. 717,937, dated January 6, 1903.

Application filed May 5, 1902. Serial No. 105,873. (No model.)

To all whom it may concern:

Be it known that I, GUY W. SMITH, a citizen of the United States, residing at San Jose, in the county of Santa Clara and State of California, have invented certain new and useful Improvements in Oil-Burners, of which the following is a specification.

My invention relates to improvements in oil-burners, the object of my invention being to provide an oil-burner which will deliver the vapor generated from the oil in a perfectly dry and highly-heated condition. For this purpose it is the object of my invention so to construct the burner that the flames of the gas generated therein shall be deflected against the retort for vaporizing the oil and shall be utilized in the most effective manner for highly heating said retort, thus generating a very dry oil-vapor and producing a perfectly smokeless flame.

A further object of the invention is to accomplish the above result in a very cheap and simple manner, so that the burner can be sold at a low price and require little care or attention to keep in order.

My invention also resides in the novel construction, combination, and arrangement of parts for the above ends hereinafter fully specified, and particularly pointed out in the claims.

In the accompanying drawings, Figure 1 is a side view of my improved burner. Fig. 2 is a vertical section thereof. Fig. 3 is a plan view of the retort, the lid being removed. Fig. 4 is a bottom plan view of the lid. Fig. 5 is a perspective view of the spreader removed.

Referring to the drawings, 1 represents the retort of the burner, and 2 the lid therefor. Said retort is provided at its upper end with an outwardly-extending flange 3, in which is formed a channel or conduit 4 for the oil. Said channel or conduit is covered with an annular sheet of asbestos 6, which is perforated, as shown at 7, to permit the oil to pass through into the channel. The oil enters the burner by means of a pipe 8 screwed into a passage 9 formed in the lid and extending downward and discharging through said aperture 7 in the asbestos sheet, which aperture registers with said passage 9. The oil flows through said aperture into said conduit, which

extends circularly for almost a complete circle and then turns upon itself as shown at 10, and extends in an inner circular path to 55 a point 11 opposite the aperture 7, when it turns inward from said path into the retort-chamber 12, formed in the main portion or retort. From said retort-chamber the vapor now formed flows outward through pipes 60 13, closed by caps 14, and discharges upwardly through apertures 15. The vapor being ignited at said apertures, the flame of the burning vapor impinges against wings or spreader-plates 16, formed on the end of a 65 spreader 17, which is laid on the top of the burner, so that said spreader-plates are vertically above said apertures. By means of said spreader-plates the flames are deflected downward and highly heat the retort and the 70 flange, thus vaporizing the oil flowing along the conduit.

An important feature of my invention resides in the means for bringing the retort to and maintaining it at a high heat. It is very 75 important that the retort should be maintained at a very high temperature in order to insure that the gas delivered therefrom shall be thoroughly vaporized and highly heated, thus giving the best result in its combustion. 80 This is insured by means of the annular flange 3 in combination with the wings 16 of the spreader extending down below the level of said flange. With this construction the effect is produced that the flames impinging 85 against the under sides of the spreader-wings and deflected therefrom are directed against the retort on the under side of the flange 3. The flange and retort are thus very highly heated. Without said flange the retort could 90 not be so thoroughly heated by means of the spreader, as the flames would tend to pass upward around the sides of the retort without being brought into close contact with the same. In my invention the flames are positively forced against the under side of the flange and also against the sides of the retort, and thus the retort is highly heated, thereby 95 completely vaporizing the gas therein and delivering it at a very high temperature.

The cover and retort are provided with registering peripheral lugs 18, which are connected together by short bolts 19, passing upwardly through the registering lugs and hav-

ing nuts 20 screwed upon the upper end thereof.

I have found that with this construction of burner I am enabled to use the very lowest grade of oil or distillate, costing about four cents a gallon. I have also operated such a burner continuously for three months in a domestic stove for cooking and heating without its needing any repair, cleaning, or to be taken apart for any purpose whatever.

I claim—

1. An oil-burner comprising a retort having an annular flange or projection extending laterally from the body thereof, conduits for the generated gas extending laterally from the lower portion of the retort, and having upwardly-directed apertures, and a spreader supported upon said retort and having wings arranged above the apertures and at such a height with reference to said flange as to deflect the flames from the apertures against

the under side of said flange to heat the retort, substantially as described.

2. In an oil-burner, the combination of a retort having a flange or projection extending laterally from the body thereof, conduits for the generated gas extending laterally from the lower portion of said retort, and a spreader comprising a cross-piece laid upon the top of the retort and having downwardly-extending arms and wings carried by said arms above the apertures in the conduits and at a height to deflect the flames impinging thereon against the under side of the flame, substantially as described.

In witness whereof I have hereunto set my hand in the presence of two subscribing witnesses.

GUY W. SMITH.
